UNITED STATES PATENT OFFICE.

JOSEPH BIJUR, OF NEW YORK, N. Y., ASSIGNEE, BY MESNE ASSIGNMENTS, TO ECLIPSE MACHINE COMPANY, OF NEW YORK, N. Y., A CORPORATION OF NEW YORK.

ENGINE-STARTING APPARATUS.

Application filed February 18, 1916. Serial No. 79,025.

This invention relates to engine-starting apparatus, and with regard to certain more specific features, to motor-operated engine-starters in which a motor-driven pinion is shifted into and out of engagement with a gear connected with the engine shaft.

One of the objects of the invention is to provide starting apparatus for internal combustion engines, which shall be of simple construction and efficient and reliable action.

Another object is to provide a simple and compact engine-starting apparatus in which the danger of damaging the parts by jamming or otherwise, is minimized or eliminated.

Another object is to provide apparatus of this general type, in which one of the gears relatively movable axially, is automatically forced into meshing condition in case the teeth of the two gears tend to meet end to end.

Another object is to provide, in a movable pinion starter, practical and efficient means for preventing the accidental rotation of the pinion, as, for example, when the engine is running.

Another object is to provide an inexpensive and efficient construction of sleeve and motor-driven pinion, enabling the parts to be easily assembled and readily disassembled in case of inspection or repair.

Other objects will be in part obvious, and in part pointed out hereinafter.

The invention accordingly comprises the features of construction, combinations of elements and arrangements of parts which are to be exemplified in the structure hereinafter described, and the scope of the application of which will be indicated in the following claims.

In the accompanying drawings, in which is shown one of various possible embodiments of this invention,

Figure 1 is an elevation, partly in section, of a preferred type of motor starter, with portions of the motor and engine illustrated conventionally.

Figure 2 is a sectional elevation on the line 2—2 of Figure 1, showing the mounting of the motor-driven gear upon the threaded sleeve.

Figure 3 is a detail view of a detent device.

Figure 4 is a detail view of the teeth of the flywheel gear and motor-driven pinion.

Figure 5 is a sectional elevation on the

line 5—5 of Figure 1, omitting certain parts to show the construction more clearly.

Similar reference characters indicate similar parts throughout the several views of the drawings.

This invention relates to apparatus for starting engines such as internal combustion engines, which are ordinarily incapable of starting without the assistance of external power. In a preferred form of the invention, the fly-wheel of the engine is provided with a gear, which, at appropriate times, is meshed with a pinion driven from an electric motor. To start the engine, power is applied to the motor, and the rotation of the motor effects both the meshing of pinion and gear and the rotation of the engine shaft through the medium of the pinion and gear. When the engine has started to rotate under its own power, the pinion and gear are disengaged by an action similar to that shown in my Patent No. 1,095,696, dated May 5, 1914, and the power is cut off from the motor either manually or automatically, as may be desired, these features of construction in themselves forming no part of the present invention.

Referring now to the accompanying drawings, there is shown in Figure 1 an engine 1 comprising a casing 2 and shaft 3, upon which is mounted a fly-wheel 4, carrying a gear 5, hereinafter referred to as the engine-driven or fly-wheel gear. A motor shown conventionally at 6, has mounted upon its shaft 7 a gear 8 meshing with the gear 9, which is fixed upon and revolvable with a sleeve 10 externally screw-threaded as at 11. Mounted upon the sleeve 10 for rotation and axial movement with respect to said sleeve is a pinion 12, hereinafter referred to as the sliding or motor-driven pinion. This pinion is provided with internal screw-threads 13 registering with the external screw threads 11 of the sleeve 10. From this it will be clear that if there is relative rotation between sleeve and pinion, there will be relative axial movement between these two elements, owing to the screw-threaded connection between them; and conversely, if relative rotation be prevented, relative axial movement will likewise be prevented. In the operation of the apparatus, power is applied to the motor to set its shaft 7 and gear 8 in rotation; this transmits motion to the gear 9 and sleeve 10; the pinion 12 does not at once acquire the

speed of rotation of the sleeve 10, due to the inertia of said pinion; and the pin 15 mounted in the pinion 12 snaps over a fairly stiff leaf or blade spring 16 mounted as hereinafter described. Thus the sleeve 10 rotates faster than the pinion 12, and this relative rotation of sleeve and pinion causes the latter to travel axially of the former, toward the left in Figure 1, and into engagement 5 with the teeth 17 of the fly-wheel gear 5. The teeth 17 of the fly-wheel gear 5 and the teeth 18 of the motor-driven gear 12 preferably have their adjacent edges tapered, as indicated in Figure 4, so that unless the teeth 15 meet almost exactly end to end, said teeth will satisfactorily mesh with one another, the tapered surfaces effecting a slight rotation of the pinion, if necessary, to insure the meshing of teeth. Usually in the operation 10 of the starting apparatus, the pinion 12 and gear 5 will be brought into mesh without any difficulty, either with or without the aid of these tapered end surfaces of the teeth 17, 18. However, the teeth 18 might jam 15 against the teeth 17 and in order to prevent the trouble that would ensue in such a case, the present invention contemplates the provision of certain mechanism, a preferred type of which will now be described.

20 In the starting operation, as the motor-driven pinion 12 travels toward the left, there is no appreciable axial thrust on the sleeve 10, because there is no opposition to the axial travel of the pinion 12. If, however, the pinion teeth 18 should jam against the fly-wheel gear-teeth 17, the pinion will 25 be unable to travel further toward the left, and since the sleeve is at this time rotated by the motor at considerable speed, there will be considerable end-thrust toward the right, upon the sleeve, since said sleeve is unable 30 to push the pinion axially toward the left. The rightward movement of the sleeve 10 is opposed by the compression of a relatively 35 light coil spring 20 mounted between the end-plates 21 on the gear 9, and a suitable portion 23 of the fixed framework. As the sleeve 10 moves toward the right, the sleeve carries with it a collar 25, surrounding the 40 sleeve and connected to a stiff coil spring 26, whose other end bears against the end flange 27 of said sleeve. The collar is, of course, rotating at the same speed as the sleeve and as the collar abuts against the left end 28 of 45 the motor-driven pinion 12, the frictional contact between collar and pinion or the increased friction at the pinion threads, or both, causes the pinion to rotate slightly, enough to bring the pinion teeth 18 into 50 mesh with the fly-wheel-gear teeth 17. Then the spring 20, which at this time is under considerable compression, forces the sleeve 10 and with it the pinion 12, leftward, so that the pinion is thus brought fully into 55 mesh with the fly-wheel gear 5. In this way,

the jamming of the teeth of pinion and gear is almost instantaneously relieved and any damage to the parts of the apparatus is prevented by the prompt relief afforded by the co-operation of spring 20 and associated 70 parts.

The leftward movement of the sleeve 10 is limited by a fixed portion 30 of the frame, into which is mounted the fixed pin or shaft 31, carrying the sleeve 10. 75

In the usual action of the apparatus, that is, when the teeth 17 and 18 mesh without appreciable abutting end to end, the leftward shifting of the pinion is cushioned and limited by the spring 26 and a dished washer 33 80 of spring steel surrounding the sleeve 10 adjacent the outer or right-hand face of the collar 25. In this action, the washer 33 is flattened out and the spring 26 compressed to such an extent as will cause the pinion to 85 turn with the sleeve and thus start the engine.

When the engine has begun to rotate under its own power, the pinion 12, now driven from the gear 5 instead of driving it, rotates faster than the motor-driven sleeve 10, and this excess of speed causes the pinion to travel along the sleeve toward the right, out of engagement with the gear 5. As the pinion 12 approaches the rightward limit 95 of its travel, the pin 15 thereon begins to strike against the projecting apex 34 of the fixed blade spring 16, as indicated in solid lines in Figure 3; the spring yields, to allow the pin to pass by the apex 34 thereof. 100 A loose washer 35 prevents the pinion 12 from jamming against the gear 9 or parts revolvable therewith. By this time the power may be shut off from the motor and the motor-driven sleeve 10 come to rest. 105 The spring 16 offers enough resistance to the pin 15 so that the pin does not pass by the spring without the exertion of considerable torque upon the pinion 12 and hence this acts as a detent, and serves to prevent 110 the accidental rotation of the pinion 12 and the consequent possible contacting of gear and pinion, owing to the vibrations of the apparatus when the engine or car is running.

In an earlier part of the description, the gear 9 has been referred to as being mounted upon the sleeve 10. A preferred mounting for the gear is illustrated in Figures 1, 2 and 5 as comprising a pair of end-plates 21, each bolted as at 36 to the gear 9, the two end-plates together providing a cup or socket for the left end of the spring 20, whose resistance to compression keeps the end-plates 21, gear 9 and sleeve 10 forced toward the left in Figure 1. The pinion and end-plates are mounted on the squared reduced portion of the sleeve 10, so that rotation of the gear 9 effects rotation of the sleeve 10. The gear 9 abuts the shoulder 37 on the sleeve 10. The end-plates have 115 120 125 130

internally projecting flanges 38 engaging in a peripheral groove 39 in the sleeve, so that when the end-plates are bolted in position as indicated in Figures 1, 2 and 5, the flanges 38 together with the shoulder 37 of the sleeve 10 hold the gear 9 securely against sliding movement upon said sleeve.

The operation of the device is as follows:

When the engine is to be started, power is applied to the motor, to set its shaft 7 and pinion 8 in rotation. This rotates the gear 9 and sleeve 10. The pinion 12 does not acquire the speed of rotation of the sleeve 10, owing to the inertia of the pinion or other means. This relative rotation of sleeve and pinion, the former at a higher speed than the latter, causes the pinion to travel to the left until its teeth 18 engage the teeth 17 on the gear 5 mounted upon the fly-wheel 4 of the engine 1. Ordinarily, the teeth 18 and 17 will mesh; and the leftward travel of the pinion 12 is cushioned and limited by the tapered coil spring 26, or the dished spring washer 33. Further rotation of the motor causes the rotation of the pinion 12, since further leftward movement of the pinion is prevented; this sets the fly-wheel gear 5 in rotation, and starts the engine. The tapering of the teeth 17 and 18 (Figure 4) facilitates the inter-meshing of the same. If, however, the teeth 17 and 18 meet end to end, so that leftward movement of the pinion 12 is prevented, a rightward movement of the sleeve 10 is caused, since the pinion 12 and sleeve 10 must have a relative axial movement owing to their relative rotation and the screw-threaded mounting of the pinion. The rightward movement of the sleeve 10 is opposed by the light compression spring 20. The rightward movement of the sleeve and parts mounted thereon brings the spring washer 33 against the left end 28 of the pinion 12 and the compression or flattening of the latter as well as a possible compression of the spring 26 exerts pressure on the pinion, and the increasing friction between the rotating collar 25 and the stationary pinion 12 or between the threads 45 of the pinion and sleeve, or both, finally forces the latter to rotate slightly, enough to bring its teeth 18 into mesh with the teeth 17 of the fly-wheel gear 5. It may be noted that by this arrangement of using a light spring in conjunction with the relatively heavy spring 26, there is a complete cushioning of the shock occasioned not only by the rightward axial movement of the sleeve, but the application of torque to the 50 pinion to relieve the jamming condition is also gradual. This is here accomplished without sacrificing the heavy spring action when the parts are gripped together in cranking the engine. It may be noted that if the spring 26 is of tapered cross section

as shown in the drawings, with its lesser cross section on the end toward the pinion, many of the advantages of the separate light spring may be obtained.

After the slight rotation of the pinion 12 to relieve the incipient jamming condition, its leftward movement is no longer opposed by the teeth 17 and it is shifted toward the left by the expansion of the spring 20. The teeth 17 and 18 are thus 70 brought into mesh, and further rotation of the motor serves to start the engine in the same manner as if no incipient jamming had occurred. When the engine has begun to rotate under its own power, disengagement 75 of the fly-wheel gear 5 and the pinion 12 is effected, preferably as set forth in my Patent 1,095,696, hereinbefore referred to; this movement being accelerated if at this time the power is shut off from the motor. 80 When the pinion 12 approaches the rightward limit of its travel along the sleeve 10, the pin 15 on the pinion snaps over the spring 16 on the gear, and when the pinion has come to rest, the co-operation of spring 90 16 and pin 15 serves as a detent to prevent the accidental rotation of the pinion, due to the vibration of the apparatus while the engine or car is in motion.

From the above, it will be seen that there 95 is provided apparatus in which the objects of the invention are realized, and other advantageous results obtained.

As various changes might be made in the above construction, and as the above invention might be embodied in different forms, it is intended that all matter set forth in the above description and in the accompanying drawings, shall be interpreted as illustrative and not in a limiting sense.

Having thus described my invention, what I claim as new and desire to secure by Letters Patent is:

1. In apparatus of the class described, in combination, an engine, a driving connection therefor including normally disengaged gears relatively movable to bring the teeth of said gears into mesh, and means for automatically effecting relative rotation of said gears by movement into contact with one of them to bring them into mesh when their teeth meet end to end.

2. In apparatus of the class described, in combination, an engine, a driving connection therefor including a normally disengaged gear and pinion relatively movable to bring the teeth of gear and pinion into mesh, and means movable into contact with the pinion and acting automatically upon the jamming of pinion teeth against gear teeth, to rotate the pinion into mesh with the gear.

3. In apparatus of the class described, in combination, an engine, a gear connected to the engine, a pinion means whereby the pinion is moved into engagement with the gear

during the starting operation, and means for automatically rotating the pinion and actuated into contact therewith when the pinion teeth and the gear teeth meet end to end.

- 5 4. In apparatus of the class described, in combination, a driving connection for an engine starting motor including a normally disengaged gear and pinion relatively movable axially to bring the gear teeth and pinion teeth into mesh, and means acting automatically upon an incipient jamming of gear teeth against pinion teeth end to end, to effect a relative rotation of gear and pinion by operative contact with one of them 10 to thereby bring said gear teeth and said pinion teeth into mesh.

5. In apparatus of the class described, in combination, an engine-driven gear, a motor-driven pinion shiftable axially into and 20 out of engagement with said gear, means effective after the meshing of gear teeth and pinion teeth, for limiting the axial movement of the pinion and simultaneously forcing said pinion to rotate, said last-named 25 means being automatically effective to force the rotation of the pinion when the pinion teeth and gear teeth meet end to end.

6. In apparatus of the class described, a 30 drive comprising a rotatable shaft, a driving member mounted thereon for rotary movement therewith and longitudinal movement thereof, said shaft having a radially projecting member, and a substantially flat spring secured to one face of said member 35 and having a hump portion, said spring being located in a plane at right angles to the axis of rotation of said shaft, said driving member having a projection adapted to be engaged by said hump portion when such 40 driving member is in normal position.

7. In apparatus of the class described, a 45 drive comprising a rotatable screw shaft, a pinion threaded thereon, a gear drivingly attached to the shaft, and a substantially flat spring secured to one face of the gear and having a hump portion, said pinion having a projection adapted to be engaged by said 50 hump portion when the pinion is in normal position.

8. In apparatus of the class described, in combination, an engine-driven gear, a motor-driven pinion slidably axially into and out of engagement with said gear, means 55 for limiting the axial movement of the pinion into engagement with the gear, and means for frictionally engaging the pinion to rotate the same when during a starting operation the pinion teeth and gear teeth meet end to end.

- 60 9. An apparatus of the class described, in combination, an engine-driven gear, a motor-driven pinion axially movable into mesh therewith, an axially movable sleeve upon which said pinion is mounted, means adapted 65 to exert a relatively light cushioning

effect to cushion and limit the axial movement of the pinion into engagement with the gear, and means offering a relatively heavy resistance to relative axial shifting of sleeve and pinion during a jamming of 70 the teeth, whereby a relatively strong frictional drive between sleeve and pinion is effected to rotate the pinion and thereby break said jam.

10. In apparatus of the class described, in combination, an engine-driven gear, a motor-driven pinion axially movable into mesh therewith, a sleeve on which said pinion is mounted, and means adapted to exert a relatively light cushioning effect to cushion and limit the axial movement of the pinion into engagement with the gear, said means offering a relatively heavy resistance to relative axial shifting of sleeve and pinion during a jamming of the teeth, whereby 80 a relatively strong frictional drive between sleeve and pinion is effected to rotate the pinion and thereby break said jam.

11. In apparatus of the class described, in combination, an engine-driven gear, a 90 motor-driven gear, a sleeve having a reduced portion upon which said motor-driven gear is mounted, a pinion upon said sleeve adapted to travel into mesh with said engine-driven gear, and means fitting into a 95 peripheral groove in said reduced portion to prevent relative axial movement of gear and sleeve.

12. In apparatus of the class described, in combination, an engine-driven gear, a 100 motor-driven pinion shiftable axially into and out of engagement with said gear, a sleeve upon which said pinion is mounted, a motor-driven gear upon a squared end of said sleeve, a pair of end-plates secured to said gear and together forming a cup, internally projecting flanges upon said end-plates engaging in a peripheral groove in said squared end of said sleeve, and a spring 105 fitted in said cup and bearing against a fixed portion of the apparatus, whereby an axial thrust is maintained upon said sleeve.

13. In apparatus of the class described, in combination, an engine driven gear, a 110 longitudinally movable driven sleeve externally threaded, a pinion threaded on said sleeve for axial movement into and out of mesh with said gear, and means for limiting such axial travel of the pinion on the sleeve after such pinion has meshed with the gear 115 and for rotating said pinion into mesh with the gear in case of the abutting of the gear teeth and the pinion teeth.

14. In apparatus of the class described, in combination, an engine-driven gear, a 120 motor-driven sleeve externally threaded and mounted for axial movement, an internally threaded pinion mounted on said sleeve for axial movement into and out of mesh with 125 said gear, means resiliently limiting the 130

- axial travel of the pinion on the sleeve after the pinion has meshed with the gear, to force the pinion to rotate the gear, said sleeve being mounted for axial movement 5 against the action of a spring, whereby, when the pinion teeth and gear teeth meet end to end and further axial travel of the pinion on the sleeve is thereby prevented, the continued rotation of the sleeve effects 10 an axial movement of the sleeve to bring said resilient means into engagement with the pinion to rotate the pinion into mesh with the gear, said spring thereupon restoring the sleeve to its initial axial position 15 and thereby simultaneously moving the pinion into mesh with the gear.
15. In apparatus of the class described, in combination, an engine driven gear, a motor, a pinion, a rotary member driven 20 from said motor on which said pinion is mounted, means adapted to move said pinion into mesh with said gear, and means aside from said rotary member tending to apply a rotary force to said pinion as its 25 teeth meet those of said gear in approaching meshing position.
16. In apparatus of the class described, in combination, an engine driven gear, a motor, a pinion driven from said motor, means 30 adapted to mesh said pinion with said gear, and a device having separate resilient means providing different resistances to compression, into operative relation with which said pinion is brought as it goes into mesh.
- 35 17. In apparatus of the class described, in combination, an engine driven gear, a motor, an endwise movable threaded member driven from said motor, a pinion threaded on said member in position to move there- 40 on into mesh with said gear, and a device actuated by endwise movement of said threaded member adapted to move said pinion relatively to said gear into meshing position upon the teeth of said pinion and gear 45 meeting end to end.
18. In apparatus of the class described, in combination, an engine driven gear, a motor, a threaded member driven from said motor, a pinion threaded on said member in position 50 to travel on its threads into mesh with said gear, and means engaging the entering end of said pinion adapted to apply a rotary force thereto upon the teeth of said pinion meeting those of said gear end to end.
- 55 19. In apparatus of the class described, in combination, an engine driven gear, a motor, a non-rotary spindle, a threaded sleeve mounted on said spindle and freely 60 rotatable and driven from said motor, and a pinion threaded upon said sleeve in position to enter into mesh with the teeth of said gear.
- 65 20. In apparatus of the class described, in combination, an engine driven gear, a motor, a rotary threaded member driven 70 from said motor, a pinion threaded upon said member in position to enter into mesh with said gear, and means independent of the threads of the pinion and member and adapted upon the teeth of said pinion meeting those of said gear end to end to increase the rotary force upon said pinion at a rate faster than the jamming force thereon from said threaded member is increased.
21. In apparatus of the class described, in combination, an engine driven gear, a motor, a threaded member, a pinion on said threaded member driven from said motor in position to enter into mesh with said gear, and a single device adapted to cushion the shock 75 of entry of said pinion within said gear and actuated by the threaded member to apply a rotary force to said pinion upon the teeth thereof meeting those of said gear end to end.
22. In apparatus of the class described, a drive comprising normally disengaged gears relatively movable to bring the teeth of said gears into mesh, and means movable relatively towards and into contact with one of said gears and adapted to slightly rotate the latter in the event of the abutting of said teeth. 80
23. In apparatus of the class described, a drive comprising normally disengaged gears relatively movable to bring the teeth of said gears into mesh, and means operative as an incident to the abutting of said teeth and movable into contact with one of said gears to slightly rotate it to overcome 85 such abutting condition.
24. In apparatus of the class described, a drive comprising normally disengaged gears relatively movable to bring the teeth of said gears into mesh, and friction means movable into contact with one of said gears to rotate it upon the abutting of said teeth. 90
25. In apparatus of the class described, a drive comprising normally disengaged gears relatively movable to bring the teeth of said gears into mesh, and means normally out of contact with but adapted to apply a gradually increasing rotative pressure to one of said gears upon the abutting of said teeth. 105
26. In apparatus of the class described, a drive comprising normally disengaged gears relatively movable to bring the teeth of said gears into mesh, and means for applying a gradually increasing frictional rotative pressure to one of said gears upon the abutting of said teeth. 115
27. In apparatus of the class described, a drive comprising normally engaged gears, one of which is moved axially to bring the teeth of the two gears into mesh, and rotatable means movable relatively to and into contact with the axially movable gear to slightly rotate the latter in the event of the abutting of said teeth. 125
28. In apparatus of the class described, 130

6
a drive comprising a rotatable shaft, a driving member mounted thereon for rotary movement therewith and for longitudinal movement thereof into engagement with a member of the engine to be started, and means carried by said shaft and movable into engagement with the driving member to slightly rotate it in the event of the arrest of its longitudinal movement during the rotation of said shaft.

29. In apparatus of the class described, a drive comprising a rotatable shaft, a driving member mounted thereon for rotary movement therewith and for longitudinal movement thereof into engagement with a member of the engine to be started, said shaft being mounted for longitudinal movement, and means carried by said shaft and moved by the longitudinal movement of the shaft into engagement with the driving member to slightly rotate it in the event of the arrest of its longitudinal movement during the rotation of said shaft.

30. In apparatus of the class described, a drive comprising a rotatable screw shaft, a pinion threaded on the shaft for rotary movement therewith and for longitudinal movement thereof into engagement with a member of the engine to be started, and means carried by said shaft and movable into contact with the pinion to slightly rotate it in the event of the arrest of its longitudinal movement during the rotation of said shaft.

35. 31. In apparatus of the class described, a drive comprising a rotatable screw shaft, a pinion threaded on the shaft for rotary movement therewith and for longitudinal

movement thereof into engagement with a member of the engine to be started, and means for cushioning the full longitudinal movement of the pinion in its engagement with the engine member and for slightly rotating such pinion in the event of its partial longitudinal movement due to the arrest thereof.

32. In apparatus of the class described, a drive comprising a rotatable screw shaft, a pinion threaded on the shaft for rotary movement therewith and for longitudinal movement thereof into engagement with a member of the engine to be started, said shaft being mounted for longitudinal movement, and means mounted on the shaft and forming a stop for the full longitudinal movement of the pinion and a rotatable actuating device adapted to slightly rotate the pinion in the event of its partial longitudinal movement and the longitudinal movement of the shaft.

33. In apparatus of the class described, a drive comprising a rotatable screw shaft, a pinion threaded on the shaft for rotary movement therewith and for longitudinal movement thereof into engagement with a member of the engine to be started, and yielding means mounted on the shaft to cushion the full longitudinal movement of the pinion and to slightly rotate the pinion in the event of its partial longitudinal movement due to the arrest thereof.

In testimony whereof, I have signed my name to this specification this fifteenth day of February, 1916.

JOSEPH BIJUR.
